CLOSURE SUPPORT

Josias F. Smythe, Portland, Oreg.

Application March 8, 1946, Serial No. 653,108

4 Claims. (Cl. 16—92)

1

This invention relates to a novel support for horizontally slidable closures, such as doors, windows and gates.

A particular object of the invention is to provide a support for sliding closures which will eliminate the need for supporting and guiding rails and rollers and which will simplify the mounting of such closures.

A further object of the invention is to provide a support of the above described character which is so constructed and arranged that the normal thrust of the closure will carry it to a fully opened or closed position as it is moved past a midway or intermediate position.

Still a further aim of the invention is to provide a supporting structure which will slightly elevate the closure during its movement to or from a fully opened or fully closed position to thus prevent binding of the bottom edge of the closure with a surface therebeneath.

Other objects and advantages of the invention will hereinafter become more fully apparent from the following description of the drawings, which illustrate preferred embodiments thereof, and wherein:

Figure 1 is an elevational view showing the closure support applied to a sliding closure and with the closure in a fully closed position;

Figure 2 is a similar view showing the closure in an intermediate or partially opened position;

Figure 3 is a view similar to Figures 1 and 2 but showing the closure in a fully opened position;

Figure 4 is a view similar to Figure 1 of a slightly modified form of the closure support; and

Figure 5 is a view similar to Figure 4 of another arrangement of the closure support.

Referring more particularly to the drawings, wherein like reference characters designate like or corresponding parts throughout the several views, and referring particularly to Figures 1 to 3, 6 designates a substantially upright surface such as a wall of an enclosure which is provided with an entrance opening 7 which is adapted to be closed by a sliding closure or door 8. It is to be understood that the closure 8, herein disclosed as a door, could likewise be a window, gate or any other closure capable of upright sliding movement.

The closure support comprising the invention includes a pair of links 9 and 10 which are pivotally connected at 11 and 12, respectively, to the surface 6 above the closure 8. Similar links 13 and 14 are pivotally connected at corresponding ends thereof at 15 and 16, respectively, to the closure 8. A tie bar 17 is provided with corresponding cross-heads 18 and 19 at the ends thereof. As clearly illustrated in Figures 1 to 3, the pivot points 11 and 12 and the pivot points 15 and 16 are disposed at substantially the same

2

horizontal level and the distances between such pivot points is greater than the length of the cross-heads 18 and 19. Likewise, lengths of the links 9, 10, 13 and 14 are substantially equal and, further, said links are each longer than the cross-heads 18 and 19.

Links 9 and 10 project upwardly from their pivoted ends and have their free ends pivotally connected to the ends of the cross-head 18 at 20 and 21, respectively. Links 13 and 14 depend downwardly from their pivots 15 and 16 and are pivotally connected at their free ends to the ends of the cross-head 19 at 22 and 23.

The parts 9 to 23, inclusive, constitute the link and tie-bar support comprising the invention as disclosed in Figures 1 to 3 and designated generally 24. Where, as in Figures 1 to 3, in order to provide a balanced support two of the link and tie-bar supports 24 are utilized.

As the closure 8 is moved from its fully closed position of Figure 1, the thrust which is thereby exerted on the tie-bar 17 will cause the link 10 to swing clockwise and will cause the link 13 also to swing clockwise. After the pivot points 21 and 22 have crossed their dead center positions in moving the closure to its closed position, the links 9 and 14 will swing slightly in a counter-clockwise direction to permit the clockwise swinging movement of the links 10 and 13. The clockwise swinging movement of links 10 and 13 will

tend to elevate the tie-rod 17 to a limited extent thereby slightly elevating the closure 8. When the closure 8 has reached an intermediate or half opened position the link and tie-rod support 24 will be disposed as shown in Figure 2. As the closure 8 moves past its position in Figure 2 toward its position of Figure 3 the weight of the closure exerts a thrust on the tie-rod and link support which urges the closure to a fully opened position. As the closure 8 is moved beyond its dead center position of Figure 2 toward its position of Figure 3, the lower end of the tie-rod 17 will be swung towards the right which will cause a slight clockwise swinging movement of the links 9 and 10 and also a clockwise swinging movement of the links 13 and 14. As the closure 8 approaches its fully opened position of Figure 3, tie-bar 17 will cross the pivot points 12 and 15 and the links will assume their position of Figure

3 as the closure reaches its fully opened position. Further, as the closure moves from its position of Figure 2 to its position of Figure 3 it will be lowered slightly so that in its position of Figure 3 it will be at the same level as when fully closed,

as seen in Figure 1. The operation of only one of the links and tie-bar supports 24 has been described but it will be readily apparent that both of said supports 24 will operate in exactly the same manner. Moving the closure 8 from its open position of Figure 3 to its closed position

of Figure 1, the operation of the tie-rod and link support 24 is the same as heretofore described in reference to the opening of the closure 8.

A modified form of the tie-rod support is shown in Figure 4 for use where there is insufficient space above the closure for employing the upper pair of links. In this form of the invention the closure frame is designated 25, the entrance opening 26 and the sliding closure 27. A bracket or hanger 28 is secured to the frame 25 above the level of the closure 27 and is provided with a stud 29 on which the upper end of a modified tie-rod 30 is pivoted. Two links 31 and 32 are pivoted at 33 and 34, respectively, to the closure 27 on substantially the same horizontal plane. The tie-rod 30 at its opposite, lower end is provided with a cross-head 35 the ends of which are pivotally connected at 36 and 37 to the lower, free ends of the links 31 and 32, respectively. As in the form of the invention previously described, two of the tie-bar or rod and link connections, designated generally 38, are provided to support the closure 27.

As the closure 27 is moved to a fully closed position as seen in Figure 4, the tie-bar or rod 30 is swung counterclockwise on its pivot 29 which additionally causes a slight counterclockwise movement of the link 32 to permit the pivot 36 to cross its dead center position after which the links 31 and 32 swing clockwise so that when the bar 30 is perpendicular the links 31 and 32 will be in the same position as the links 13 and 14 in Figure 2. In moving beyond this, the dead center position of the closure 27, the bar 30 will continue to swing counterclockwise and across the pivot 33 and as the closure reaches its fully opened position the link 32 will have assumed the position of the link 31 in Figure 4 and the link 31 will be substantially in a perpendicular position.

In Figure 5 another embodiment of the invention for use in mounting a slide enclosure 39, such as a gate, is disclosed. In this view the closure 39 is shown in a fully closed position and the link and tie-bar support, designated generally 40 is substantially identical to that disclosed in Figure 4 except that it is inverted. The lower end of the tie-bar 41 of the support 40 is pivoted at 42 to a post 43. Two links 44 and 45 are pivoted at 46 and 47, respectively, to the closure 39 and extend upwardly therefrom. The tie-bar 41 likewise extends upwardly and is provided at its upper end with a cross-head 48 to which the ends of the links 44 and 45 are pivotally connected at 49 and 50, respectively. As only a single support 40 is provided in this form of the invention, a pair of rollers 51 may be mounted on another gate post 43 for engaging above and beneath a rail of the closure 39 for guiding it in its opening and closing movement.

As the operation of the support 40 is identical with that of the support 38, except that it is inverted, a further description of the movement of the tie-bar 41 and links 44 and 45 required during the opening and closing movement of the closure 39, is deemed to be unnecessary.

In each form of the invention as previously disclosed, the links are located between the closures or frames and the tie-bar cross-head.

Various other modifications and changes are likewise contemplated and may obviously be resorted to without departing from the spirit and scope of the invention as hereinafter defined by the appended claims.

I claim as my invention:

1. In a support for sliding closures, a pair of links pivotally connected at corresponding ends thereof to a closure, a pair of links pivotally connected at corresponding ends thereof to a frame of said closure, and a tie-bar having cross-heads at each end thereof, the free ends of one of said pair of links being connected to the ends of one of said cross-heads and the free ends of the other pair of links being pivotally connected to the free ends of the other of said cross-heads for supporting the closure for sliding movement relative to the frame.

2. In a support for sliding closures, a pair of links pivotally connected at corresponding ends thereof to a closure, a pair of links pivotally connected at corresponding ends thereof to a frame of said closure, and a tie-bar having cross-heads at each end thereof, the free ends of one of said pair of links being connected to the ends of one of said cross-heads and the free ends of the other pair of links being pivotally connected to the free ends of the other of said cross-heads for supporting the closure for sliding movement relative to the frame, the ends of said links which are pivotally connected to the cross-heads being more adjacent than the ends thereof which are pivoted to the closure and frame.

3. In a support for sliding closures, a pair of links pivotally connected at corresponding ends thereof to a closure, a pair of links pivotally connected at corresponding ends thereof to a frame of said closure, and a tie-bar having cross-heads at each end thereof, the free ends of one of said pair of links being connected to the ends of one of said cross-heads and the free ends of the other pair of links being pivotally connected to the free ends of the other of said cross-heads for supporting the closure for sliding movement relative to the frame, said links each being of a greater length than the cross-head.

4. In a support for sliding closures, a pair of links pivotally connected at corresponding ends thereof to a closure, a pair of links pivotally connected at corresponding ends thereof to a frame of said closure, and a tie-bar having cross-heads at each end thereof, the free ends of one of said pair of links being connected to the ends of one of said cross-heads and the free ends of the other pair of links being pivotally connected to the free ends of the other of said cross-heads for supporting the closure for sliding movement relative to the frame, the first-mentioned pivot points of each of said pairs of links being spaced a greater distance apart than the length of the cross-head, and the links connected to the frame, being disposed above the level of the links connected to the closure, and the ends of the pairs of links connected to said crossheads constituting the remote ends of said links.

JOSIAS F. SMYTHE.
